(57) **CLAIM**

The ornamental design for a treadmill as shown and described.

DESCRIPTION

FIG. 1 is a front, right side, top perspective view of a treadmill showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof; and,
FIG. 8 is an enlarged view of the boxed region noted by the number 8 in FIG. 1 so as to illustrate the details thereof.
The evenly broken line showing of the treadmill is for the purpose of illustrating portions of the article that forms no part of the claimed design. The dot-dash lines that demarcate claimed areas in FIGS. 1 & 8 have been included to show enlargement for clarity. The lines themselves do not form part of the claimed design.
